Marshall & Lucke

UNITED STATES PATENT OFFICE.

JAMES T. HAMBAY, OF HARRISBURG, PENNSYLVANIA.

TUBULAR-FRAME WHEELBARROW.

1,196,776.

Specification of Letters Patent.

Patented Sept. 5, 1916.

Application filed March 19, 1915. Serial No. 15,429.

To all whom it may concern:

Be it known that I, JAMES T. HAMBAY, a citizen of the United States of America, and resident of the city of Harrisburg, county 5 of Dauphin, State of Pennsylvania, have invented a new and useful Improvement in Tubular-Frame Wheelbarrows, of which the following is a specification.

My invention relates to tubular-frame 10 wheelbarrows and the object of the invention is to improve the construction of the same so that they will be more satisfactory in use than heretofore. In the mounting of the tray on the frame it has been the practice to secure the same by rivets or bolts to cross-braces spanning between the two sides of the frame, the cross-braces being secured to the tubular-frame at each end by clamping the same thereto as hereinafter described. As it would weaken the frame too 15 much at these points to make bolt holes therethrough, the securing of the braces to the frame has been dependent upon frictional engagement. This has resulted in the 20 serious defect of permitting the tray to slide forward on the frame against the wheel, caused by the striking of the frame or wheel of the barrow against obstructions. While 25 this defect has been recognized for years and many thousands of barrows are made each 30 year, no effective method for preventing it has yet been put into practice.

The object of my invention is to remedy this defect by simple and effective means.

In the following I have described, in connection with the accompanying drawings, a 35 form of tubular-frame barrow showing my improvement in connection therewith.

In said drawings, Figure 1 is a perspective view of a tubular-frame barrow provided with my improvement in one form; Fig. 2 is a fragmentary side view on an enlarged scale and partly in section, showing another form of my improvement; Fig. 3 40 is a fragmentary view, partly in section and on an enlarged scale, of the form shown in Fig. 1; Fig. 4 is a cross-sectional view of a detail of construction along the line 4—4 in Fig. 3, looking in the direction of the 45 arrows.

Similar letters of reference indicate similar parts throughout the several views.

a indicates the tray of the barrow, prefer-

ably pressed from a single sheet of steel and free from seams, rivets and joints.

b indicates the reinforced edge of the tray which adds to the strength of the tray and gives the edges a smooth finish.

c indicates the tubular-frame, preferably formed of a single length of pipe bent to 60 shape as shown.

d indicates the wheel, *e* the axle and *f* the axle bearing, secured to the frame by a bolt *g* which passes through the frame and also serves to secure one end of front brace *h*, 65 the other end of the brace being bolted or riveted to the upper front portion of the tray.

i and *j* indicate cross-braces spanning between the two sides of the tubular-frame and secured thereto by having their ends looped over the frame and bolted as shown in Fig. 4, the bolts serving to hold the tray to the cross-braces, to secure the cross braces to the frame and to secure one end of strap *k* to 75 the same. Strap *k* is shown as bent at *l* to form a leg and then bent upwardly to form a brace *m* secured to cross-brace *j* in a manner similar to that shown in Fig. 4.

n indicates a leg-brace fastened at each 80 of its lower ends to strap *k* at the leg bend *l* and at its upper bend to the cross-brace and tray.

One form of my invention consists in lengthening the strap *k* so that it extends 85 from cross-brace *j* to axle bearing *f* where it is secured firmly to the tubular-frame by bolt *g* passing also through the axle bearing and the foot of brace *h*, a hole through the frame at this point not appreciably weakening the frame. The strap *k* thus abuts 90 against a rigid stop and holds the tray against any forward sliding movement. No part of the tubular-frame is weakened by making additional holes therethrough, yet 95 the whole structure is stiffened and strengthened.

In Fig. 1 the axle bearing *f* is shown as a "single" bearing secured to the frame by but one bolt. In Fig. 2 I have shown a 100 "double" bearing secured to the frame by two bolts. In this latter case the strap *k* would be secured to the frame by the inner bolt as shown. Instead of lengthening strap *k* I may use a short length *o* and bolt the 105 same at both ends, one end to the cross-brace

j and the other, for example, to the inner bolt of the axle-bearing. This latter form could be readily utilized in connection with barrows already constructed so as to provide them with the improvement described.

What I claim and desire to secure by Letters Patent is:—

1. In a tubular-frame wheelbarrow a cross-brace frictionally engaging the tubular frame, an axle bearing and a rigid connection fastened at one point to the cross-brace and abutting against the axle bearing at its outer end, said outer end being secured to the tubular-frame adjacent the axle bearing.

2. In a tubular-frame wheelbarrow a cross-brace frictionally engaging the tubular frame, an axle bearing and a rigid connection fastened at one point to the cross-brace and abutting against the axle bearing at its outer end, said outer end being secured to the tubular-frame by the same bolt which secures the axle bearing thereto.

In testimony whereof I have signed this specification in the presence of two subscribing witnesses.

JAMES T. HAMBAY.
